UNITED STATES PATENT OFFICE.

MANUEL PRADO, OF TACUBA, MEXICO.

ARTESIAN-WELL-DRILLING MACHINE.

1,333,442.

Specification of Letters Patent.

Patented Mar. 9, 1920.

Application filed August 12, 1919. Serial No. 316,949.

To all whom it may concern:

Be it known that I, MANUEL PRADO, a citizen of the United Mexican States, residing at Tacuba, Federal District, Mexico, 5 have invented certain new and useful Improvements in Artesian-Well-Drilling Machines, of which the following is a specification.

This invention relates to drilling machines 10 and its principal object is to produce a sudden drop of the bit, maintaining uniform the distance of the drop irrespective of the varying depths to which the drill is sunk in repeated dropping operations. This may 15 be obtained by means of an automatic arrangement for lengthening at each operation the auxiliary cable on which the bit hangs, an extent determined by the increased depth of the well-shaft.

20 Another object of this invention is to provide the drum on which is wound the auxiliary cable of the bit, with an automatic brake which permits the cable to uncoil in proportion to the increased depth of the 25 well-shaft produced by each stroke of the bit.

These objects may be obtained by the mechanism shown in the accompanying drawing, in which:

30 Figure 1 is a lateral longitudinal elevation of the machine;

Fig. 2 is a plan view of same.

Fig. 3 is an elevation of the mechanism which raises the bit;

35 Fig. 4 is a view in detail of the automatic feeding means for the bit-carrying cable.

Regarding the drawing: (1) is the framework or frame on which is mounted the main axle (2), which is directly connected 40 with a motor or some other means of movement (not shown). The axle (2) has rigidly secured thereto a pulley (3) which through belt (4) transmits the movement to the loose pulley (5) on the shaft (6), which,

45 on its end outside of the frame, carries a pulley (7) connected with the belt (8) to transmit movement in the reverse direction to pulley (9) secured to shaft (10). Mounted on the shaft (10) is a pinion (11), which meshes with the gear-wheel (12) mounted loosely on the shaft (13). The gear-wheel (12) has rigidly secured thereto a disk (14), to which is riveted a projecting butt (15), which when turning around will push against 50 an abutment (16) riveted upon rim (17) of

the separate wheel (18) secured to the shaft (13).

Fastened to the shaft (13) is the crank (19) which by means of a pivot is connected with connecting rod (20), pivoted at (21) to 60 one end of the balance-beam (22), which has its point of support in (23). The balance-beam (22) carries two pulleys (24) and (25), through which passes the auxiliary 65 bit-carrying cable (26). The bit-carrying cable is provided at its end with a clamp (27), which engages the main cable (28). The cable (28) passes through a block or pulley (not shown) of the support (29), and is wound around the drum (30). The 70 drum (30) receives movement from the pulley (31), loosely mounted on the shaft (2) which, by means of clutch (32), driven thereby transmits reverse movement to the pulley (33), which through shaft (34), 75 moves the pinion (35) transmitting movement to the gear-wheel (36) which is connected with the shaft (37) of said drum (30).

The auxiliary cable (26) is carried by a 80 reel (38), provided at each end with a hand brake, of which the brake band (39) is operated by the lever (40), which adjusts it to allow the cable to uncoil only as much as may be necessary, as a consequence of 85 the hole produced by the drill bit. Another brake (41), when it is applied in combination with the brake (39) will set the reel, preventing it from uncoiling the cable. This brake (41) consists of the band (42), 90 one end of which is attached at (43) to the lever (44), and by means of the springs (45) it is attached to the frame (1). This lever (44) is also joined through a fastening rod (46) to the balancing-beam (22). 95 The other end of the band (42) is connected with the lever (44), by means of a screw or an adjusting nut (47). Connecting the band (42) with the frame are the fastening rod (48) and link (49).

The lever (50) serves to throw the clutch (32) and connect the pulley (31) to the shaft (2), while the lever (51) will connect the clutch (52), in order to transmit movement from the loose pulley (5).

Fig. 2, shows a lever (53) connected with the shaft (54) which through the rod (55) restrains the band brake (56) of the drum (30), in order to prevent the bit from dropping very fast after changing tools or 110

when it is necessary to lower the bit again in the well-shaft or hole made.

- The drill-bit and the side of the balance-beam to which it is connected normally tend 5 to move downwardly under the influence of gravity. When the parts are in this position and the clutch 52 is closed, so as to complete the train of connections from the main shaft 2 to the driving gear 12, the rotation 10 of the gear 12 causes the projection 15 thereon to engage the abutment 16 on the wheel 18 and thereby drive the crank shaft 13, which through the connecting rod 20 raises the drill-bit and parts connected therewith. 15 When the balance-beam and the drill-bit have been raised sufficiently, which is at the time that the connecting rod passes its "dead center," the drill-bit and its side of the balance-beam fall by gravity, thus drilling 20 the well-shaft. During the movement of the drill-bit, the abutment 16 moves in advance of the projection 15 and, therefore, the speed and force of the downward movement of the bit are not limited or opposed 25 by the speed of the motor or the movement of the connecting parts.

When the balance-beam moves to drop the drill-bit, the cord 46 pulls the end of the lever 44 and thus releases the brake band 30 42 to permit the cable to be unwound sufficiently to compensate for the increased depth of the well-shaft incidental to each drop of the drill-bit. This movement of the cable is limited to the actual increase of 35 depth by the brake band 39 which constantly engages the drum 38 and which has sufficient braking action to overcome the momentum of the cable in this movement. This compensates for the increased depth of 40 the well-shaft or hole by lengthening the cable at each operation and insures uniform strokes for the drill-bit at each operation.

In order to raise the bit from the well-shaft, the lever 50 is operated to throw in 45 the clutch 32, which causes the drum 30 to

rewind the cable 28 thereon. To permit the cable 28 and the bit to be again lowered, the brake 56 is released by operating the lever 53.

Having thus described my invention what I claim is:

1. A drilling machine, comprising a balance-beam and means for operating the same; a reel; a drill-bit; an auxiliary bit-carrying cable operated by said balance-beam and wound on said reel; a brake connected to said reel; means connected with the balance-beam for automatically releasing said brake at the drill-bit dropping operation of said balance-beam; and spring means for normally maintaining said brake 50 in operative position.

2. A well-drilling machine, comprising an oscillating balance-beam and means for operating the same; a loose driving connection between said balance-beam and the operating means therefor, whereby the balance-beam may move independently of said operating means in its drilling movement and may be connected to the operating means during the return movement; a reel; a drill-bit; a drill-bit-carrying cable wound on said reel; an adjustable brake for said reel; and another brake connected with one end of the balance-beam so as to alternately hold and release the reel and thus the cable, at each 65 70 oscillation of the balance-beam.

3. A drilling machine comprising a bit; a bit-carrying cable; winding means for said cable; means for reciprocating said cable and bit in the well-shaft; and a brake for 80 said winding means adapted to permit the unwinding of the cable at each operation of the reciprocating means an amount equal to the increased depth of the well-shaft incidental to the drilling operation, so as to 85 maintain uniform the length of the repeated strokes of the bit by the reciprocating means.

In testimony whereof I have affixed my signature.

MANUEL PRADO.
